UNITED STATES PATENT OFFICE.

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

FEELER IN TRANSFERRER ARM.

Application filed October 21, 1927. Serial No. 227,801.

This invention relates to improvements in weft detectors of the type mounted on regularly moving transmitters, and it is the principal object of the invention to provide 5 means for preventing the indicating element from moving accidentally endwise on the transmitter arm while at the same time permitting said element to be moved very easily by the detector.

10 In Patent No. 1,372,316 to Ryon there is shown a loom having a transmitter arm which moves downwardly on every detecting beat of the loom to present the weft detector carried by the arm to the top of the bobbin 15 in the shuttle. The detector is made to slide along a bobbin which is substantially exhausted into engagement with a plunger. The plunger is moved outwardly so that when raised with the transmitter arm it will 20 engage and rock an indicating lever to initiate replenishment. In the form of detector shown in Patent No. 1,551,219 also to Ryon, the plunger is held in position by a spring detent which enters a conical groove 25 formed in the plunger. The plunger is moved by a force derived from the detector and it is found that the spring detent interferes with the proper action of the weft detector in that the spring detent must be 30 moved to releasing position by the detector before the plunger can be moved to indicating position. It is an important object of my present invention to provide lightly 35 acting resilient means acting on a cylindrical portion of the plunger to hold the same against creeping movement in the transmitter arm but acting to permit the weft detector to move said plunger on the first part of the indicating movement thereof.

40 The lever on which the detector is mounted ordinarily is held in raised position by a tension spring interposed between said lever and a part of the transmitter arm, and it is a further object of my invention to utilize this 45 spring to yieldingly hold the plunger in non-indicating position, there being a rocking lever between the spring and the plunger so formed as to tend normally to increase its pressure against the plunger as the detector 50 descends, thereby preventing misindications by improper movements of the detector.

With these and others objects in view which will appear as the description proceeds, my invention resides in the combina-

tion and arrangement of parts hereinafter 55 described and set forth in the claims.

In the accompanying drawings wherein I have shown one embodiment of my invention

Fig. 1 is a vertical section taken through 60 a portion of a transmitter arm having my invention applied thereto, with the plunger held in non-indicating position.

Fig. 2 is a view similar to Fig. 1 but with 65 the parts moved to indicating position.

Fig. 3 is a vertical section on line 3—3 of Fig. 1, and

Fig. 4 is a vertical section on line 4—4 of Fig. 2.

Referring to the drawings a transmitter 70 arm 10 is provided with a heel 11 and tip 12 to engage respectively the butt and body of a bobbin B. The transmitter arm is provided with a pair of spaced parallel walls 13 which define a vertical slot 14. Extending 75 across said slot is a pin 15 on which is mounted a carrier lever 16 held raised normally by a tension spring 17 interposed between said lever and screw 17' carried by the transmitter arm. A weft detector 18 is supported on said lever 16 and is provided with a yarn engaging roughened lower end 19. Said detector is provided with a hook 20 which bends over a finger 21 and extends into a notch 22 formed between said finger and a second finger 23. A compression 80 spring 24 interposed between a shoulder on the detector and a washer 25 tends normally to hold the detector in low position relatively to the lever 16. Said detector is 85 guided between a pair of spaced arms 26 and extends upwardly through a slot 27 formed in the lever 16.

Under normal conditions the transmitter arm is moved downwardly by mechanism set 90 forth in said patents to Ryon on each detecting beat of the loom and when sufficient yarn is present the detector will engage the bobbin and be held against longitudinal movement therealong, but when insufficient 95 weft is present the detector slides along the bobbin as indicated in Fig. 2. The carrier lever 16 is so formed as to have the greater part of the weight thereof to one side of the pin 15 and as the transmitter arm comes 100 to a sudden stop in its descent the inertia of said carrier lever will move the same downwardly against the action of spring 17. The

matter thus far described is the same as set forth in said patents and also in my co-pending application Serial No. 120,491.

My improvements relate more particularly to the means for controlling the indicating plunger and in carrying my invention into effect I provide a plunger or indicating element 40 which is mounted for free sliding movement in web 41 of the trans-
ferrer arm extending between the walls 13. The left end of said plunger may be reduced and lie in proximity to the detector as at 42. The web is provided with a pocket 43 and that part of the plunger normally moving in the pocket is reduced as at 44 to define shoulders 45.

A pin 46 extends between the walls 13 and has pivotally mounted thereon a plunger retaining lever 47 having a depending finger 48 and an upwardly extending arm 49 which is curved to be eccentric with respect to the pin 46. The upper end of said arm 49 is concaved, as shown at 50, Fig. 4, and is proportioned to receive a part of the spring 17 at a point lying to the left of the pin 46. The finger 48 rests on a cylindrical portion of the plunger 40, being held there by action of the spring 17 the axis of which is bent as shown in Figs. 1 and 2, to exert downward pressure on the retaining lever 47. A tail 51 on the carrier lever 16 engages a portion of the web 41 when the trans-
ferrer arm is in its extreme upper position and spring 17 is always under tension. The right end of pocket 43, as shown in Fig. 1, defines a shoulder 52 which serves as a stop for finger 48.

Under normal conditions the finger 48 exerts downward pressure on the plunger 40 to hold the same against endwise movement in the trans-
ferrer arm, the restraint thus exerted increasing as the carrier lever 16 descends relatively to the trans-
ferrer arm. When the detector moves along an exhausted bobbin from the position shown in Fig. 1 to that shown in Fig. 2, it engages the end 42 of the plunger and moves the same to the right until the right hand shoulder 45, defined by the reduced portion 44 of the plunger, arrives under the finger 48, at which time said finger will move behind the shoulder and continue the movement of the plunger to the right to the indicating position shown in Fig. 2. The force accomplishing this result is derived from the spring 17 and movement of the finger 48 to the right is arrested by the shoulder 52, and should the plunger continue its movement to the left it will be arrested by the left hand shoulder 45.

From the foregoing it will be seen that I have provided an indicating plunger for a regularly moving loom trans-
ferrer arm which is held against accidental endwise movement by pressure exerted on a cylindrical portion thereof, and that because of

the construction set forth the detector is not materially resisted in the first part of its indicating movement. It will further be seen that the energy which moves the plunger is derived from the same spring as that which holds the carrier lever in raised position.

Having thus described my invention it will be apparent that changes and modifications may be made therein by those skilled in the art without departing from the spirit and scope of the invention and I do not wish to be limited to the details herein disclosed, but what I claim is:

1. In weft detecting mechanism for a loom having a regularly moving trans-
ferrer arm with a carrier pivoted thereto provided with a side slipping weft detector which has an indicating movement when the weft is substantially exhausted, a plunger normally in retracted position and located for engagement with the detector when the latter has an indicating movement, a retaining device mounted on the trans-
ferrer arm independent of the carrier and having lateral engagement with the plunger, and a single resilient device to hold the carrier and detector normally raised with respect to the trans-
ferrer arm and also to hold the retaining device against the plunger to prevent accidental movement of the latter.

2. In weft detecting mechanism for a loom having a regularly moving trans-
ferrer arm with a carrier pivoted thereto provided with a side slipping weft detector which has an indicating movement when the weft is substantially exhausted, a plunger slidably mounted on the trans-
ferrer arm and normally retracted and having a portion for direct engagement with the detector when the latter has an indicating movement, a retaining lever independent of the carrier pivoted to the trans-
ferrer arm and having a finger to have lateral engagement with the plunger, and a single resilient element operatively connected to the carrier and retaining lever to hold the carrier and detector normally raised and also to hold the retaining lever in engagement with the plunger to prevent accidental movement of the latter.

3. In weft detecting mechanism for a loom having a regularly moving trans-
ferrer arm with a carrier pivoted thereto provided with a side slipping weft detector which has an indicating movement when the weft is substantially exhausted, a plunger slidably mounted on the trans-
ferrer arm and having a portion for direct engagement with the detector to be moved endwise by the latter at indication of weft exhaustion, a retaining lever pivoted to the trans-
ferrer arm and having a finger normally in engagement with the plunger, and a tension spring interposed between the carrier and a fixed part of the trans-
ferrer arm to hold the carrier and detector normally raised, said spring also hav-

ing engagement with the retaining lever to hold the same yieldingly against the plunger to prevent accidental movement of the latter.

4. In weft detecting mechanism for a loom having a regularly moving transerrer arm with a carrier pivoted thereto provided with a side slipping weft detector which has an indicating movement when the weft is substantially exhausted, a plunger slidably mounted in the transerrer arm and located for engagement with the detector when the latter has an indicating movement, a retaining lever having lateral engagement with the plunger, and a tension spring interposed 10 between the carrier and a fixed part of the transerrer arm effective to hold the carrier and detector normally raised and to exert a force transverse of the length thereof on said retaining lever to hold the latter yieldingly against the plunger to prevent accidental movement of the latter.

5. In weft detecting mechanism for a loom having a regularly moving transerrer arm with a carrier pivoted thereto provided with a side slipping weft detector which has an indicating movement when the weft is substantially exhausted, a plunger slidably mounted in the transerrer arm and positioned for engagement with the detector 25 when the latter has an indicating movement, a retaining lever pivoted to the transerrer arm and having lateral engagement with the plunger, and an expansible resilient device interposed between a fixed part of the transerrer arm and the carrier and normally tending to hold the carrier and detector in raised position, said device increasing in length on a detecting beat of the loom as the carrier and detector move toward the 30 surface to be detected, said expansible device having contact with and exerting a force transverse of the length thereof against the retaining lever, said force increasing after the resilient device expands at the time the 35 carrier and detector move downwardly relatively to the transerrer arm to exert an increasing retaining force on the plunger to prevent accidental movement of the latter.

6. In weft detecting mechanism for a loom having a regularly moving transerrer arm with a carrier pivoted thereto provided with a side slipping weft detector which has an indicating movement when the weft is substantially exhausted, a plunger slidably mounted on the transerrer arm and located 50 for engagement with the detector at the time of indication of weft exhaustion, a retaining lever normally having lateral engagement with the plunger, a resilient device to hold the carrier and detector in raised position and also exerting a force against the retaining lever to hold the same against the plunger to prevent accidental movement of

the latter, and means defining a shoulder on 65 said plunger for engagement with the retaining lever after movement of the plunger has been initiated by the detector, said retaining lever and shoulder cooperating with the resilient device to move the plunger slidably with respect to the transerrer arm.

7. In weft detecting mechanism for a loom having a regularly moving transerrer arm with a carrier pivoted thereto provided with a side slipping weft detector which has an indicating movement when the weft is substantially exhausted, a plunger slidably mounted on the transerrer arm and located for engagement with the detector when the latter has an indicating movement, a retaining lever pivoted to the transerrer arm and having a finger located for lateral engagement with the plunger, a single spring interposed between a fixed part of the transerrer arm and the carrier and also engaging the retaining lever, said spring normally holding the carrier and detector in raised position and also holding the retaining finger yieldingly against the plunger, and means defining a shoulder on the plunger for cooperation with said finger after the detector 80 has initiated sliding movement of the plunger to continue the sliding movement by the cooperation of said finger, spring and shoulder.

8. In weft detecting mechanism for a loom having a regularly moving transerrer arm with a carrier pivoted thereto provided with a side slipping weft detector which has an indicating movement when the weft is substantially exhausted, a plunger slidably mounted on the transerrer arm and located for engagement with the detector when the latter has an indicating movement and being of reduced diameter at a point intermediate the ends thereof to define spaced shoulders, 95 a retaining lever having a finger in lateral engagement with the plunger, a single resilient device interposed between a fixed part of the transerrer arm and the carrier and normally holding the carrier and detector in raised position and also engaging the retaining lever to hold the same yieldingly against the plunger, sliding movement of the plunger under influence of the detector bringing one of said shoulders into engagement with the retaining lever so that by cooperation of the single resilient means, said retaining lever and said shoulder the plunger will be continued in its movement, the other of said shoulders acting as a stop to limit endwise 100 movement of the plunger by engagement with said retaining lever.

In testimony whereof I have hereunto affixed my signature.

RICHARD G. TURNER.
